INVENTOR

BY
Dorsey Cole
ATTORNEY

UNITED STATES PATENT OFFICE.

JOHN W. MURPHY, OF CORNING, NEW YORK, ASSIGNOR TO CORNING GLASS WORKS, OF CORNING, NEW YORK, A CORPORATION OF NEW YORK.

WORKHOLDER.

Application filed March 28, 1923. Serial No. 628,309.

To all whom it may concern:

Be it known that I, JOHN W. MURPHY, a citizen of the United States, residing at Corning, in the county of Steuben and State 5 of New York, have invented new and useful Improvements in Workholders, of which the following is a specification.

This invention relates to means for holding rough iron casting rigidly on the spindles of multiple-tooled turret lathes, so that the tools carried by the turret of the 10 lathe can be successively brought into use to finish the castings without the operator being required to make alterations or adjustments to the castings during the finishing 15 operations.

For the purpose of illustrating a specific embodiment of my invention, I have chosen to show the same used in connection with 20 the finishing of the rough castings of the hinged together halves of glass blowing molds, the inside contour of such castings being machined out by means of forming roughing and finishing tools, while the 25 halves are closed.

In the accompanying drawings:—

Figure 1, is a side elevation of a portion 30 of a multiple-tooled turret lathe, showing the lathe spindle with the work fastened thereto by means of the holder forming the subject matter of this invention, and a portion of the tool-carrying turret, one of the tools being in engagement with the work to be finished;

Fig. 2, is a view of the work-holder showing only a portion of the lathe spindle, as seen from the arrow X, Fig. 1;

Fig. 3, is a transverse section taken on the line 3—3 of Fig. 2;

Fig. 4, is a view of the work-holder as seen from the arrow Y, Fig. 2;

Fig. 5, is a transverse section taken on the line 5—5 of Fig. 4, and

Fig. 6, is an end view of the work-holder.

Iron molds which are used for forming blown glass articles (whether such molds are used on glass blowing machines, or in hand shops) are composed of two parts or halves A, and a, that is to say, they are formed so as to open and shut. The two halves of the molds are held by a hinge pin which must be a certain distance from the center of the bored mold, so as to properly locate the mold on the blowing machine or glass-worker's dummy, as the case may be.

The mold castings usually have their exterior surfaces shaped to conform somewhat to their interior contour.

Referring now to the drawings, wherein is shown the casting of an electric light bulb mold adapted to be used on glass blowing machines, the casting which is to be finished on the lathe has an annular flange B that forms the top of the mold, a tapering portion C that forms the neck of the mold, and an outwardly flared portion F which terminates in an enlarged portion G. The tapering portion C of the casting has a bead D formed thereon adjacent to the flange B, a groove E being formed between the flange B and the bead D. Formed integral with each of the halves of the casting are arms H (Figs. 2 and 3), the extremities of which are provided with tubular bosses K through which the hinge pin of the mold is passed.

It is to be noted that the castings above described only form the upper portion of the complete mold, and that attached to the enlarged portion G is a semi-spherically shaped mold bottom (not shown).

In the operation of finishing the mold castings in the machine shop, the bosses K of the two halves of the mold are first bored, then the castings are transferred to a multiple tooled turret lathe for machining the inside contour.

The means for holding the castings on the turret lathe comprises a circular plate 10 that is threaded to the end of the lathe 90 spindle 11 as shown by Fig. 1. Formed integrally with the plate 10 but spaced therefrom by means of a pair of webs 13, is a base 12 that is slightly greater in size than the plate 10.

Formed in the base 12 and offset from its center a distance equal to the distance between the center of the internal bore of the casting and the center of the bore in the bosses K through which is passed the hinge 100 pin of the mold, is an aperture 14 (Fig. 2) having a diameter equal to the diameter of the hinge pin of the mold.

Carried on the side of the base 12 opposite the aperture 14, is a slotted plate 15 105 which is adapted to be locked in position by means of a screw 16. The plate 15 is mounted on the face of the base 12 in offset relation to a line projected through the center of the aperture 14 and the center of the 110

plate 12. The inner surface of plate 15 is arcuately formed so as to snugly fit against the vertical edge of the flange B of the casting when such casting is being positioned on the base 12. If a number of similar castings are being finished consecutively, one setting of the plate 15 is sufficient, as the purpose of this element is to assist in centering the castings on the base 12.

10 The castings are designed to be held at right angles (90°) to the face of the base 12 so that the longitudinal axis of the castings will correspond to the axis of the spindle of the lathe. For this purpose, I provide clamps 17 that are carried by posts 18 extending from the base 12 parallel to the axis of the spindle 11. The clamps 17 are so formed that they can be used to press down on to the flange B of the 20 castings, and such clamps are mounted for slidable movement on the posts 18.

The posts 18 have one of their ends passed through openings formed in the base 12. These ends are threaded and nuts 19 25 are screwed tight against the underside of the base. The opposite or outer ends of the posts 18 are also threaded. Carried on the posts, between the clamps 17 and the outer threaded extremities of the posts 30 are a plurality of tubular spacers 20. These spacers are of varying lengths, and their purpose is to enable nuts 21 which are threaded on to the extremity of the posts, to be positioned away from the face of 35 the base 12, whereby the operator can draw down on the nuts very tightly. The number of spacers 20 is determined by the thickness of the flange B of the castings, or the distance of the clamps 17 from the base 12.

40 A block 22 (Fig. 6), which is supported by two posts 23 and 24 projecting outwardly from the base 12, is provided with an aperture 25 that is in line with the aperture 14 formed in the base.

45 When the castings are being positioned on the base 12, a rod 26 having a diameter approximating the diameter of the hinge pin of the mold, is passed through the aperture 25, then through the bosses K of the castings and then through the aperture 14. A groove is formed in the lower end of the rod 26 for the reception of a set-screw 27 that is mounted in the base 12 as shown by Figs. 2, 4 and 5.

50 For the purpose of holding the halves of the castings together, I utilize a yoke 28 that is swingingly mounted on a post 29 extending from the base 12 diametrically opposite the aperture 14. The yoke is 55 mounted a suitable distance from the base

12 and its arms carry set-screws 30 that engage the side of the castings adjacent to the intersection of the tapering portions F and the portions C thereof, as shown by Fig. 3.

65 The design of the parts is such that the operator can spread one of the halves of the castings without moving the other half, by loosening one of the clamps 17 and the set-screws 30, and swinging the yoke out of the way. The reverse of this procedure puts the halves of the castings back in position, ready to go on with the machining.

70 By this device clamping and closing the halves of mold castings as it does, any kind of castings of this general type with fixed distance between the longitudinal axis of the casting and the hinge pin thereof, can be held on a lathe to advantage, whereby tools of very large cutting surfaces can be 80 used to form the desired contour in the casting without clatter, or the castings being able to move in the holder.

Having thus described my invention what I claim and desire to secure by Letters Patent is:—

85 1. In a lathe work-holder for forming a central cavity in an article comprising separable hinged members, the combination of a base plate having a pin projecting therefrom adapted to pass through the pivot holes of the separable members, clamping and centering means on the base plate for the base of the article, and a yoke pivotally carried by the base plate and adapted 90 to hold the upper portion of the separable members together.

95 2. In a lathe work-holder for forming a central cavity in an article comprising separable hinged members, the combination of a base plate having a pin projecting therefrom adapted to pass through the pivot holes of the separable members, clamping and centering means on the base plate for the base of the article, and a yoke pivotally mounted on the base plate and having 100 adjustable means to hold the upper portion of the separable members together.

105 3. In a lathe-work holder for articles having hinged members in which a cavity is 110 to be formed, the combination of a base plate having clamping and centering means, a head frame rigidly mounted thereon and spaced therefrom, and a rod having its opposite ends supported in the plate and frame and having its intermediate portion 115 contained within the hinge of the article.

In testimony whereof I hereunto sign my name this 24th day of March, 1923.

JOHN W. MURPHY.
